UNITED STATES PATENT OFFICE.

BERNARD BRIODY, OF YOUNGSTOWN, OHIO, ASSIGNOR TO TRUSCON STEEL COMPANY, OF YOUNGSTOWN, OHIO, A CORPORATION OF MICHIGAN.

CONTRACTION JOINT.

Application filed July 9, 1924. Serial No. 724,945.

This invention relates to the construction of concrete roadways, particularly to those provided with metal strips for the purpose of forming contraction joints, and the object of this invention is to provide means for connecting the ends of alined strips.

A further object of this invention is to provide removable means adapted to be mounted on the tops of the dividing strips for the purpose of forming narrow troughs in the concrete roadway adapted to receive tar or asbestos.

In the accompanying drawing, Fig. 1 is a plan of a section of roadway. Fig. 2 is a perspective of two ends of a dividing strip joined with my improved connector. Fig. 3 is a section on the line 3—3 of Fig. 2. Fig. 4 is a section of concrete roadway on the line 4—4 of Fig. 3.

Similar reference characters refer to like parts throughout the several views.

In order to make sure that concrete roadways 1 will crack along straight lines when the plastic mass contracts or when it is displaced vertically by frost, strips 2 of sheet metal are embedded therein to act as dividers to locate the cracks. The adjacent edges of roadway slabs may be caused to rise and fall together by forming these strips with longitudinal channels 3 which extend into and receive similarly formed portions of the adjacent slabs. The strips are formed with holes 4 in the walls of the channels to receive supporting stakes to hold the strips in position while the concrete is being placed and with other holes 5 to receive transverse reinforcements for the slabs.

The adjacent ends of two strips 2 may be kept in alinement by a connector comprising the plate 6 having struck-up tongues 7 so spaced from the plane of the plate as to just admit the ends of the strips. The

width of these strips is preferably a little less than the thickness of the slab, preferably from one-half inch to one inch less, and channel shaped cap strips 8 are mounted on the upper edges of the dividing strips, the tops of these cap strips being even with the finished upper surface of the roadway. This cap strip is left in as long as possible before being removed, but it must be taken out before the concrete has set sufficiently to prevent its removal. The space thus left is then filled with a plastic mass 9, such as asphalt or tar, which prevents the edges of the concrete from chipping. The connectors 6 hold the dividing strips in alinement so that the cap strips may be readily fitted thereto.

These contraction joints are not intended to prevent a roadway from cracking, but they do cause the cracks to occur along straight lines and the slight spaces thus formed are filled by the plastic material 9.

I claim:

1. In a concrete roadway, alined channel-shaped strips adapted to be embedded end to end therein for the purpose of forming a contraction joint, and means connecting the ends of adjacent strips comprising a plate adapted to lie on one side of each strip within the channel thereof and supported by the lower wall of the channel and struck-up tongues adapted to lie on the opposite side of each such strip, said tongues extending in opposite directions from the middle of the plate.

2. Means for alineing the adjacent ends of strips adapted to be embedded in concrete roadways to produce contraction joints, comprising a metal plate provided with tongues at both ends lying on opposite sides of the adjacent ends of the strips.
